DESIGN FOR A MULTIPLE FLAME WELDING TIP

Marvin R. Scott, Elizabeth, N. J., assignor to Ox-weld Acetylene Company, a corporation of West Virginia

Application December 13, 1938, Serial No. 81,761

Term of patent 14 years

To all whom it may concern:

Be it known that I, Marvin R. Scott, a citizen of the United States, residing at Elizabeth, in the county of Union and State of New Jersey, have invented a new, original, and ornamental Design for a Multiple Flame Welding Tip, of which the following is a specification, reference being had to the accompanying drawing, forming a part thereof.

Fig. 1 is a perspective view of a multiple flame welding tip illustrating my new design;

Fig. 2 is a side elevational view of the welding tip disclosed in Fig. 1; and

Figs. 3 and 4 are front and rear elevational views, respectively, of the welding tip disclosed in Fig. 2.

I claim:

The ornamental design for a multiple flame welding tip, substantially as shown.

MARVIN R. SCOTT.
